Primary Examiner — T. Chase Nelson*Assistant Examiner* — Ania Aman(74) *Attorney, Agent, or Firm* — Reinhart Boerner Van Deuren P.C.(57) **CLAIM**

I claim the ornamental design for the filter element, as shown and described.

DESCRIPTION

FIG. 1 is a perspective view of the filter element; FIG. 2 is a side view of the filter element of FIG. 1; FIG. 3 is a side view of the filter element of FIG. 1 showing the side opposite that shown in FIG. 2; FIG. 4 is a back view of the filter element of FIG. 1; FIG. 5 is a front view of the filter element of FIG. 1; FIG. 6 is a top view of the filter element of FIG. 1; and, FIG. 7 is a bottom view of the filter element of FIG. 1. In the drawings, the broken lines depict unclaimed subject matter only and form no part of the claimed design.

1 Claim, 6 Drawing Sheets# US D794,082 S
